United States Patent Office

Des. 180,724
Patented July 30, 1957

180,724

CALCULATING MACHINE

Raymond Spilman, Darien, Conn., Roger Engel, Forest Hills, N. Y., and Richard Hollerith, Jr., Upper Montclair, N. J.

Application December 11, 1956, Serial No. 44,160

Term of patent 14 years

(Cl. D64—11)

Fig. 1.

Fig. 2.

Fig. 3

Fig. 4

Fig. 1 is a front perspective view of a calculating machine showing our new design;

Fig. 2 is a side elevational view thereof;

Fig. 3 is an elevational view of the side opposite to that shown in Fig. 2; and

Fig. 4 is a rear elevational view thereof.

The broken line illustration of the roll of tape shown in Figs. 2, 3 and 4 is for illustrative purposes only.

We claim:

The ornamental design for a calculating machine, as shown and described.
